Atty's

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,387,114.

Specification of Letters Patent. Patented Aug. 9, 1921.

Application filed January 16, 1920. Serial No. 351,779.

To all whom it may concern:

Be it known that I, FRED S. CARR, a citizen of the United States, and a resident of Newton, in the county of Middlesex, Commonwealth of Massachusetts, have invented an Improvement in Fasteners, of which the following description, in connection with the accompanying drawings, is a specification, like characters on the drawings representing 10 like parts.

This invention pertains to separable fasteners. The fasteners which I have elected to show in the present application for illustrative purposes is a modification of the 15 fastener shown in my copending application Serial No. 351,776 filed January 16, 1920, and is intended to provide a spring of somewhat greater resiliency than that shown in said copending application.

20 In the drawings, wherein I have shown one illustrative embodiment of a preferred construction constituting one form of my invention:

Figure 1 is a view of two pieces of fabric 25 held together by a fastener;

Fig. 2 is a section on the line 2—2 of Fig. 1;

Fig. 3 is a view of the socket member from the spring side; and

30 Fig. 4 shows a plurality of fasteners connecting two pieces of fabric.

Referring to the drawings, I have shown a stud 5 having a head and a neck co-operating with a socket including a casing plate 6 containing a spring 7, which may be of the well known "Kohinoor" type. The spring 7 provides terminal portions 8, 9 passing at each side of a stud-receiving aperture 10 in the socket plate and terminating under a 35 lip 11 died inwardly from the spring-retaining rim of the socket casing. I preferably provide means for spacing the terminal portions of the spring apart, and I may conveniently do so by striking from the lip 11 a depending lip 12 between the ends of the spring. I may, if desired, provide additional means for holding down those portions of the spring adjacent the stud-receiving aperture in the socket in any suitable 40 way, but I prefer to strike up portions 13, 14 of the socket casing beneath which the secondary spring portions 15, 16 are received, preferably permitting considerable to-and-fro movement of said spring portions so that the entire spring action will 55

not come from the bends 17, 18 but may start from the bends 19 and 20.

By the before described means of securing the spring in the casing without a dome, as is usually provided in sockets containing 60 springs of the "Kohinoor" type, I have eliminated those difficulties which attend the manufacture of sockets having domes slotted for the entrance of the springs, and at the same time I have provided a type of socket 65 well adapted for use in connection with a notched stud-receiving aperture, the advantages of which are fully described in my pending application, Serial No. 307,111, filed June 27, 1919, and in my copending application filed herewith, Serial No. 351,776, filed January 16, 1920. It will be understood that the use of the spring supports 13, 14 is optional, and that these may be omitted or other supplemental spring-supporting devices may be substituted therefor.

It will also be understood that, while I have shown and described a preferred form of one embodiment of my invention, changes involving omission, substitution, alteration 80 and reversal of parts, and even changes in the mode of operation, may be made without departing from the scope of my invention, which is best defined in the following claims.

Claims:

1. A socket for stud and socket fasteners comprising, in combination, a casing having a continuous lip flanged inwardly to retain a spring, said lip being extended at one side to overlie the ends of the spring. 85
2. A socket for stud and socket fasteners comprising, in combination, a casing having a continuous lip flanged inwardly to retain a spring, said lip being extended at one side to overlie the ends of the spring, and having 90 at the extended side a depending portion spacing the ends of the spring.

3. A socket for stud and socket fasteners comprising, in combination, a casing having a continuous flanged-over rim, a spring 100 of the "Kohinoor" type within said casing, said casing being domeless and providing means operatively supporting the stud-engaging portions of the spring against displacement when the stud is entered in the 105 socket.

4. A socket for stud and socket fasteners comprising, in combination, a casing having an aperture therethrough providing notch means opposing undesired separation of stud 110

and socket under forces resulting from lateral strain, said casing containing a spring of the "Kohinoor" type and providing means remote from the stud-receiving aperture for opposing displacement of the spring in a direction transverse to the general plane of the socket when the stud is entered in the socket aperture.

5. A socket for stud and socket fasteners comprising, in combination, a casing containing a spring, said casing having thread-receiving apertures punched therein, the mate-

rial from said apertures being bent back and overlying in spaced relationship portions of said spring, thereby to oppose displacement of said spring in a direction transverse to the general plane of the socket, while permitting movement of the adjacent spring portion in a direction generally parallel to the general plane of the socket. 15 20

In testimony whereof I have signed my name to this specification.

FRED S. CARR.
